UNITED STATES PATENT OFFICE.

FRAZER W. GAY, OF NEWARK, NEW JERSEY.

SIGN.

1,362,284.

Specification of Letters Patent. Patented Dec. 14, 1920.

Application filed August 15, 1919. Serial No. 317,837.

To all whom it may concern:

Be it known that I, FRAZER W. GAY, a citizen of the United States, residing at Newark, in the county of Essex and State of

5 New Jersey, have invented certain new and useful Improvements in Signs; and I do hereby declare the following to be a full, clear and exact description of the invention, such as will enable others skilled in the art to 10 which it appertains to make and use the same, reference being had to the accompanying drawings, and to characters of reference marked thereon, which form a part of this specification.

15 The present invention has reference, generally, to improvements in illuminated signs, advertising devices and devices of a similar nature; and the invention relates, more particularly, to a novel, cheap and simple construction of illuminated and self-luminous sign or the like.

The invention has for its principal object to provide a sign or the like the characters or devices of which are coated with a phosphorescent material capable of being actuated by exposure to light to produce a luminosity thereof, rendering the same easily visible in darkness, and combining therewith a light source adapted to flood the sign 30 with light at intermittent periods, not only for the purpose of rendering the sign visible in the reflected light, but at the same time actuating the phosphorescent material to store the light therein for rendering the sign 35 luminous when the light from the source is cut off.

Another object of the present invention is to provide in combination with the sign having the above stated characteristics a 40 transparent screen interposed between the light source and said sign, said screen to carry an additional sign or device only visible when illuminated by light from said source, and through which the luminous 45 sign in the rear thereof may be viewed when light from said source is cut-off.

Other objects of the present invention, not at this time more particularly enumerated, will be clearly understood from the following detailed description of the same.

50 With the various objects of the present invention in view the same consists, primarily, in the novel combined illuminated and luminous sign or the like hereinafter 55 set forth; and the invention consists, furthermore, in the novel arrangements and

combinations of the various devices and parts, as well as in the details of the construction of the said parts all of which will be hereinafter more fully described, and then finally embodied in the appended claims.

The invention is clearly illustrated in the accompanying drawings, in which:—

Figure 1 is a face view of a sign illustrating one embodiment of the principles of my present invention.

Fig. 2 is a face view of a sign illustrating a modified structure embodying the principles of my present invention, in which a transparent screen is employed carrying a sign or device visible when exposed to light rays; Fig. 3 is a face view of said modified structure illustrating the visibility of the luminous main sign through said screen when external light rays are cut off; and Fig. 4 is a transverse section, taken on line 4—4 in said Fig. 2, the same being drawn on an enlarged scale.

Similar characters of reference are employed in the above described views, to indicate corresponding parts.

Referring now to said drawings the reference character 1 indicates a sign board or other suitable base upon which the characters or devices making up the desired sign are mounted, and 2 indicates the said characters or devices mounted on said sign board or base 1. The exposed faces of the characters or devices 2 are treated or coated with a covering of phosphorescent material capable of being actuated by exposure to light rays for the purpose of rendering the same self-luminous when said exposure to light rays is discontinued. This material may be crystalline phosphorescent zinc sulfid or other similar phosphorescent sulfid or similar material.

Suitably arranged in proximity to the face of said sign board or base 1, so as to 100 easily direct their rays upon the said coated characters or devices 2 mounted thereon, are one or more electric lamps 3, or other suitable source of artificial light. When said electric lamps are used the same may 105 be supplied with electric current from a suitable source through the interconnecting circuit wires 4. There may be included in said circuit, if desired, an automatic time switch device 5, which will serve to turn on 110 and off the lamps 3 at suitable intervals, and intermittently if desired.

The object of the structure thus described is to provide a sign, the characters or devices of which, being treated with a phosphorescent material of the kind above mentioned, 5 will not only be illuminated by the rays of light emanating from the lamps 3, but which will also absorb or store said light by reason of the actuation of the phosphorescent material, so that when the lamps 3 are turned 10 off, the sign will become self-luminous, and will consequently glow in darkness, so that the characters or devices may be easily visible and readable in the darkness. When the automatic time control switch 5 is employed 15 it is set so that the light of the lamps will not be interrupted for a period so long that the phosphorescent material will entirely lose its glowing properties, and consequently intermittent intervals, of proper time duration, providing alternate light and darkness 20 will not only intermittently actuate the self-luminous qualities of the sign, but will also provide a novel and attractive device due to the alternated characters of its illumination. 25

I have mentioned a cheap phosphorescent material as the preparation with which the characters or devices 2 are treated, but I do not wish to limit myself exclusively to 30 the use of such material alone, since I may also employ for the purpose a radium charged phosphorescent material as well, either alone or in combination with an area of the ordinary phosphorescent material so 35 that if the sign loses its luminosity from the light actuated material, it will still be rendered glowing or visible by reason of the radio activity due to the presence of the radium element.

40 Referring now more particularly to Figs. 2 to 4 inclusive of the drawings, I have illustrated therein a slight modification of the sign above described. In this modified structure I employ the sign board or base 1 upon 45 which are mounted the characters or devices 2 treated with the phosphorescent material or similar substance. The face of the sign board or base 1 is painted or otherwise colored to provide a back-ground 6 adapted to 50 conform in color to the color of the treated characters or devices 2, when the latter are subjected to illumination by external light. Supported in front of and in suitable proximity to said sign board or base 1 are the 55 electric lamps 3. Interposed between the face of said sign board or base 1 with its treated characters or devices 2 and the lamps 3 is a transparent screen 7, preferably in the form of a mesh or netting. Painted 60 upon said screen 7 are characters or devices 8 which become easily visible when the lamps 3 are turned on to illuminate the face of said screen, by reason of their reflection of such external lights, but which become 65 invisible when the lamps 3 are turned off and

light shines through the screen from behind. The purpose of having the back-ground 6 conform in color to the color of the characters or devices 2 is to prevent any optic confusion or in other words to prevent visibility of the characters or devices 2 through the screen 7 when the lamps 3 are turned on, which would tend to confuse or interfere with the clear visibility of the characters or devices 8 of the screen 7 under 70 such conditions. The screen 7 being transparent not only will the light rays from lamps 3 illuminate and render visible the characters or devices 8, (as shown in Fig. 2), but said rays will also pass through the 80 transparent screen 7 and will thereupon actuate the treated characters or devices 2, so that when the lamps are turned off the latter will become self-luminous, in the manner already above described. When the 85 lamps 3 are turned off, direct light no longer falls upon the face of the screen 7, and consequently the characters or devices 8 are no longer rendered visible by reflection of said light, and since in the absence of direct 90 external light rays upon the face of the sign board or base 1 the treated characters or devices 2 become self-luminous, and since the luminosity of said characters or devices 2 occurs in back of said screen 7, it follows 95 that the light resulting from said luminosity will shine through the transparent screen 7 so that the characters or devices 2 become visible in place of the characters or devices 8 through which the light rays of such 100 luminous characters 2 pass, the screen providing no bar to such visibility (as illustrated in Fig. 3 of the drawings). While I have mentioned the use of mesh or netting as the preferable material for the screen 105 7, I do not wish to confine myself thereto, since I may employ a sheet of transparent glass, celluloid, or similar material, upon which the characters or devices 8 are inscribed with a transparent paint, stain or 110 varnish, which will be visible by reflection of direct light flooding the face of the screen but which will become visible when light shines or is transmitted through the same and the screen from the rear, so that the 115 luminosity of the characters or devices 2 may consequently readily shine through such a screen and prepared character or device 8, so as to permit the characters or devices 2 to be clearly visible when viewed through 120 the screen.

Of course, it will be clearly understood that the respective legends formed by the characters or devices 8 upon the screen 7 and by the characters or devices 2 upon the 125 sign board or base 1, may be made complementary one to the other, or they may be totally independent of each other, as to the meaning conveyed thereby.

I am aware that some changes may be 130

- made in the general arrangements and combinations of the devices and parts, as well as in the details of the construction of the same without departing from the scope of 5 my present invention as described in the foregoing specification, and as defined in the claims appended hereto. Hence, I do not limit my invention to the arrangements and combinations of said devices and parts as set forth in the foregoing specification, nor do I confine myself to the exact details of the construction of said parts as illustrated in the accompanying drawings.
- I claim:-
- 15 1. In a sign or the like, a base, characters mounted on said base, said characters being coated with self-luminous preparation, the face of said base being prepared to correspond in color to the color of said coated 20 characters when viewed in external light to render the same substantially invisible in such light, a transparent screen spaced forward of said base, and said screen having inscribed thereon characters visible only by 25 reflection of external light directed upon the face of said screen, said luminous characters on said base being visible through said screen and its characters in the absence of external light directed upon the face of said 30 screen.
2. In a sign or the like, a base, characters mounted thereon, said characters being treated with a substance adapted to be actuated by exposure to light for rendering the 35 same self-luminous, the face of said base being prepared to correspond in color to the color of said treated characters when viewed in external light to render the same substantially invisible in such light, a lighting 40 means in proximity to said base for shedding actuating light rays upon said treated
- characters, and a transparent screen interposed between said lighting means and said base, said screen having inscribed thereon characters visible only by reflection of external light shed by said lighting means, 45 said actuated self-luminous characters on said base being visible through said screen and its characters when said lighting means is shut off.
3. In a sign or the like, a base, characters mounted thereon, said characters being treated with a substance adapted to be actuated by exposure to light for rendering the same self-luminous, the face of said base being prepared to correspond in color to the color of said treated characters when viewed in external light to render the same substantially invisible in such light, an electric lighting means in proximity to said base for 50 shedding actuating light rays upon said treated characters, an electric circuit for supplying current to said lighting means, an automatic switch mechanism included in said circuit for intermittently turning on 55 and off the actuating light rays of said lighting means, and a transparent screen interposed between said lighting means and said base, said screen having inscribed thereon characters visible only by reflection 60 of external light shed by said lighting means, said actuated self-luminous characters on said base being visible through said screen and its characters or devices when said lighting means is shut off.
- 65 In testimony, that I claim the invention set forth above I have hereunto set my hand this 13th day of August, 1919.
